A. VON AUW

VISIBLE CARD INDEX

Filed July 29, 1926. 11

Howson and Howson

UNITED STATES PATENT OFFICE.

ALWIN VON AUW, OF BROOKLYN, NEW YORK, ASSIGNOR TO BOORUM & PEASE COMPANY, OF BROOKLYN, NEW YORK, A CORPORATION OF NEW YORK.

VISIBLE CARD INDEX.

Application filed July 29, 1926. Serial No. 125,694.

This invention relates to the overlapping type of visible index in which the cards have hinged slidable mounting and more particularly to the novel form of attachment of the 5 cards to the panel and their inter-relation with each other. In an index made according to my invention a certain duplex lateral ear is formed outside the body of the card on each side thereof. These ears are made in 10 such manner and of such relation to the body of the card that when the cards are assembled together on the panel they overlap in a non-nesting hinged relation.

One of the objects of my invention is to 15 provide an index from which individual metal carriers for the cards have been eliminated. Another object of my invention is to provide an extremely compact and simple form of card which it shall be economical 20 to manufacture and extremely easy to manipulate. Another object of my invention is to provide a card which can be cut integrally out of one piece of sheet material and which is strong at the points where strain is apt 25 to occur. Another object of my invention is to provide a perfectly flat writing surface for the cards in a visible index panel, and still another object of my invention is to provide a form of visible card index in which 30 the whole surface of both sides of the record section of a card is available for writing while the card is in the visible index. Another object of my invention is to provide a form of card whose record section can be 35 formed into an ordinary vertical index card.

In the drawings:

Fig. 1 is a plan view of one of the new index cards,

Fig. 2 is a plan view of part of the panel 40 with cards therein, one flange of the panel being partly broken away,

Fig. 3 is an exaggerated vertical section through the ears of the cards taken on the line 3—3 of Fig. 2;

Fig. 4 is a horizontal section on the line 45 4—4 of Fig. 2, while

Fig. 5 is a plan view of one corner of a modified form of card.

The novel form of visible index member or 50 card which forms the nucleus of my invention comprises a rectangular body preferably having a straight upper edge 11 and a plain duplex ear composed of two lobes 8, 9 extending laterally from each side of the body 55 near its upper edge the two lobes of each ear

being at different heights on the card. The body is hinged along a horizontal line 12 reaching from one free edge of the body to the other and generally, though not necessarily, the portion below the hinged line is 60 large enough to be a record section 10. This novel member may be used as a carrier for another card by gluing or otherwise attaching the ordinary card to the member below the hinge line 12. However, in this specification I shall describe the card as having a record section, and the remainder of the body and the duplex ears as made integrally out of one piece of sheet material. This material may be cardboard, paper or the like. Each 70 duplex ear consists of two horizontal lobes 8, 9 separated from each other by a horizontal slit which may be merely an incision in the sheet material or may be formed by cutting out a little of the material between the 75 cards to afford room for the flange of the panel. Each ear is so placed on the card that its upper edge is in line with and merges into the upper edge 11 of the body. The lower end of the juncture between the ear 80 and the body is preferably at the hinge line between the record section and the remainder of the body. Each lobe of the ear is preferably formed with both its upper and lower edges horizontal, as shown in the drawings, 85 but the edges of the tongues can be cut at any angle provided the whole ear does not project above or below the juncture of the ear with the body, i. e., each ear is of its maximum vertical dimension at its juncture with 90 the body. The lower lobe 9 may be shorter than the lobe 8 if desired, (see lobe 9' in Fig. 5) and greater ease thus obtained in attaching the card to the panel.

While the hinge line 12 can be located at 95 any level which permits it to run between free edges of the body I prefer to have the hinge line 12 located right at the lower end of the junctures between the ears and the body. The line can be formed by creasing 100 or weakening the paper or in any other manner desired.

By having ears of this kind a non-nesting card is produced with all the advantages of that type of card and none of the disadvantages.

This novel form of card is intended to be mounted on a panel or backing 6 having two opposed inwardly facing flanges 7 under which portions of the card may be 110

placed. The inner edges of these parallel flanges should be spaced apart a distance which permits the body of the card to lie therebetween giving a flat writing surface.

5 The ears being external of the body of the card are interwoven with the flanges. In mounting the card the upper lobe 8 of each ear is laid on top of the flange while the lower lobe 9 is laid underneath, the slits between the ears being deep enough to permit this. The slit can be made still deeper, if desired, thus making it possible to attach the card without flexing it, by turning the card sideways.

10 15 When a series of depending cards are mounted in the panel in this manner the body 10 of any one card should overlie the body of the card below, and the cards will then overlap. It will then be found that 20 the upper edge 11 of any card rests against the card above it at the junctures between the lower edges of the ears and the body of the upper card. It is impossible for one card to pass the other and the necessary 25 overlap is obtained. As already mentioned, the ears are so shaped and attached to the body of the card that there is no nesting. It will be observed that by my invention the necessary non-nesting engagement between 30 neighboring cards is obtained by the use of an ear on the upper card underlying the flange and the body of that card, which neither overlies nor underlies the flange, overlying the straight upper edge of the lower card, thus reducing the number of 35 portions of the card which have to be manipulated in attaching the card to the panel.

By having duplex ears projecting laterally from the body of the card and employing the body of the card to assist in maintaining the overlap, it becomes necessary 40 only to tear or cut off these duplex ears to obtain the ordinary vertical record card without any punchings therein or alterations 45 in the shape. Similarly ears can very easily be gummed onto the ordinary record card when it is desired to mount that card in a visible index. The advantages of such interchangeability will be obvious without 50 further comment. By thus having a card attached to its support or panel by means laterally outside the body of the card, the bodies of the cards lie flatly on top of each other on the flat surface in between the two 55 flanges. It is therefore possible to write with perfect ease on the cards while they are in the index, even when the cards are made of paper.

The cards are simple and yet at the same 60 time do not nest, and the index is positive in its maintenance of overlap and yet permits removal or insertion of a card without disturbing the neighboring cards.

I claim:

65 1. A visible index member comprising a

body in combination with a duplex ear projecting laterally from each side of the body and integral therewith, the two lobes of each ear being at different heights and the upper edge of each ear merging into the upper edge of the body and each ear being of its maximum vertical dimension at its juncture with the body. 70

2. A visible index member comprising a body having a straight upper edge in combination with a duplex ear projecting laterally from each side of the body, the upper edge of each ear merging into the upper edge of the body, each ear having two lobes separated by a horizontal slit, and being of its maximum vertical dimension at its juncture with the body. 75

3. A visible index card comprising a body having a straight upper edge, in combination with an ear having two lobes separated by a horizontal slit projecting laterally from each side of the body and joined thereto from the upper edge, the ears not projecting above or below their junctures with the body, said body having a hinge line running between the free side edges thereof. 80

4. A visible index card comprising a rectangular body having a straight upper edge and including a record section joined to the remainder of the body by a horizontal hinge line reaching between free edges of the body, in combination with a duplex ear projecting laterally from each side of the body, the upper edge of each ear merging into the upper edge of the body, substantially as described. 90

5. A visible index card comprising a rectangular body having a straight upper edge and including a record section joined to the remainder of the body by a hinge line, in combination with a duplex ear projecting laterally from each side of the body and joined thereto from the upper edge to the hinge line, the ears not projecting above or below their junctures with the body. 105

6. A visible index comprising a panel having opposed inwardly facing flanges in combination with a series of overlapping cards each having a body overlying the body of the card below but not overlapping the flanges, and an ear having two lobes projecting laterally from each side of the body, the upper edge of each upper lobe merging into the upper edge of the body and overlying one flange while the lower lobe underlies that flange. 110

7. A visible index comprising a panel having parallel inwardly facing flanges in combination with a series of overlapping cards each having a body overlying the body of the card below but not overlapping the flanges, said body having a straight upper edge and including a record section joined to the remainder of the body by a hinge line, in combination with a duplex ear projecting laterally from each side of the body and 120

joined thereto from the upper edge to the hinge line, the ears not projecting above or below their junctures with the body, substantially as described.

5. 8. A visible index member comprising a body having a straight upper edge in combination with a duplex ear projecting laterally from each side of the body, the upper edge of each ear merging into the upper edge 10 of the body, each ear having two lobes separated by a horizontal slit, and being of its maximum vertical dimension at its juncture with the body, the lower lobe of each ear being shorter than the upper lobe of that 15 ear.

9. A visible index comprising a panel having opposed inwardly facing flanges in combination with a series of overlapping cards each having a body overlying the body of 20 the card below but not overlapping the flanges, and an ear having two lobes pro-

jecting laterally from each side of the body, the upper edge of each upper lobe merging into the upper edge of the body and overlying one flange while the lower lobe underlies that flange, the lower lobe of each ear being shorter than the corresponding upper lobe. 25

10. A visible index member comprising a body having a straight upper edge in combination with a duplex ear projecting laterally from each side of the body, the upper edge of each ear merging into the upper edge of the body, each ear having two lobes separated by a horizontal slit, and being of its 30 maximum vertical dimension at its juncture with the body, one lobe of each ear being shorter than the other lobe of that ear, substantially as described. 35

In testimony whereof I have signed my 40 name to this specification.

ALWIN VON AUW.
